UNITED STATES PATENT OFFICE.

CHARLES E. WILLIAMS AND FREDERICK H. WEAVER, OF BALTIMORE, MARYLAND.

MUFFLER FOR EXHAUST-PIPES.

1,182,611.

Specification of Letters Patent.

Patented May 9, 1916.

Application filed June 16, 1915. Serial No. 34,365.

To all whom it may concern:

Be it known that we, CHARLES E. WILLIAMS and FREDERICK H. WEAVER, citizens of the United States, residing at Baltimore, 5 in the State of Maryland, have invented certain new and useful Improvements in Mufflers for Exhaust-Pipes, of which the following is a specification.

This invention relates to improvements 10 in mufflers for explosive engines, and has for its object to provide a muffler of simple construction and which may be readily secured in or removed from the exhaust pipe of any explosive engine, whereby the noise resulting 15 from the exhaust of the engine, as well as the back pressure upon the engine, will be overcome.

The invention consists of the novel construction and arrangement of the parts and 20 combination of parts hereinafter more fully set forth in the following specification, and pointed out in detail in the appended claims.

In the accompanying drawings, Figure 1 is a side elevation of our invention. Fig. 25 2 is a vertical longitudinal section of Fig. 1, inserted in the exhaust pipe, the latter being partly broken away. Fig. 3 is a section of Fig. 1, on the line X—X. Fig. 4 is an end view of Fig. 2.

30 Referring to the accompanying drawings, forming part of this specification, and in which like reference numerals designate like parts throughout the several views thereof, 1 designates a cylindrical tube adapted to fit within the exhaust pipe 2, and is provided with a number of integral baffle plates 3 cut from the bottom thereof and bent inwardly and a corresponding number of integral baffle plates 4 cut from the top and 35 bent inwardly, the plates 3 and 4 are slightly out of line vertically so that they overlap each other when bent inwardly, the cylindrical tube 1 is also provided with integral baffle plates 5 and 6 on opposite sides thereof, 40 of which are bent inwardly and overlap in the same manner as the plates 3 and 4. The baffle plates 5 and 6 being between the plates 3 and 4. All of the baffle plates are cut from the cylinder and are narrower at the 45 point where they join the tube and after being cut are forced into the tube 1 and then

flattened out by a suitable tool, causing them to expand and become wider than the opening from which they were cut, whereby the said baffle plates will be locked under the 55 side edges of the said opening adjacent the point where they are bent. These baffle plates cause the gases resulting from the explosions of the engine to diffuse as they pass through the muffler, thus causing them to 60 be discharged silently therefrom. The arrangement of the baffle plates causes a tortuous passage through the muffler but will not cause a back pressure of the gases passing therethrough. The muffler may be held 65 by a bolt passing through the aperture 7, or in any other suitable manner.

Having thus described our invention what we claim is:

1. A muffler for explosive engines comprising a cylindrical tube having a number of integral baffle plates bent inwardly therefrom, said plates being adapted to lock under the edge of the cylinder from which 70 they were cut.

2. A muffler for explosive engines comprising a cylindrical tube having a number of integral baffle plates bent inwardly from the bottom thereof, a similar number of integral baffle plates bent inwardly from the 75 top thereof and having their ends overlapping the ends of the upper baffle plates, a number of integral baffle plates bent inwardly from one side thereof, and a similar number of integral baffle plates bent inwardly from the other side thereof and having their ends overlapping the baffle plates 80 on the opposite side.

3. A muffler for explosive engines comprising a cylindrical tube having a number of integral baffle plates bent inwardly from the top and bottom thereof, the plates of the top being out of line vertically with, and having their ends overlap, the plates at the bottom, a number of integral baffle plates 90 bent inwardly from the opposite sides thereof, the plates of one side being cut of line vertically with, and having their ends overlap, the plates of the opposite side.

4. A muffler for explosive engines comprising a cylindrical tube having a number of integral baffle plates bent inwardly from 95

the top and bottom thereof and having their ends overlapping each other, a number of integral baffle plates bent inwardly from the opposite sides thereof and having their ends 5 overlapping each other all of said baffle plates being flattened out causing them to lock under the edge of the opening from which they were cut.

In testimony whereof we affix our signatures in presence of two witnesses.

CHARLES E. WILLIAMS.
FREDERICK H. WEAVER.
